UNITED STATES PATENT OFFICE.

STANLEY S. COVERT, OF MONTCLAIR, NEW JERSEY.

DESIGN FOR A FIREPLACE-THROAT.

42,912.

Specification for Design.

Patented Aug. 20, 1912.

Application filed June 12, 1912. Serial No. 703,313. Term of patent 14 years.

To all whom it may concern:

Be it known that I, STANLEY S. COVERT, a citizen of the United States, and resident of Montclair, Essex county, New Jersey, have invented a new, original, and ornamental Design for Fireplace-Throats, of which the following is a specification, reference being had to the accompanying drawing, forming part thereof, wherein—

Figures 1 and 2 are respectively perspective views of opposite sides of a fire-place throat showing my new design.

I claim:

The ornamental design for a fire-place throat as shown.

STANLEY S. COVERT.
